UNITED STATES PATENT OFFICE.

MORRIS WEINTRAUB, OF NEW YORK, N. Y.

DESIGN FOR A KETTLE AND STAND.

41,191.

Specification for Design.

Patented Feb. 21, 1911.

Application filed September 21, 1910. Serial No. 583,128. Term of patent 3½ years.

To all whom it may concern:

Be it known that I, MORRIS WEINTRAUB, a citizen of the United States, residing in the city of New York, borough of Manhattan, in the county and State of New York, have invented a new, original, and ornamental Design for a Kettle and Stand, of which the following is a specification, reference being had to the accompanying drawing, forming a part thereof.

The figure is a perspective view of a kettle and stand, illustrating my new design.

I claim:

The ornamental design for a kettle and stand, as shown.

MORRIS WEINTRAUB.
